Primary Examiner — Keli L Hill*Assistant Examiner* — Harold E Blackwell, II(74) *Attorney, Agent, or Firm* — BELLES KATZ LLC(57) **CLAIM**

The ornamental design for a hanging bracket, as shown and described.

DESCRIPTION

FIG. 1 is a top front perspective view of a hanging bracket according to our new design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate portions of a hanging bracket that form no part of the claimed design.
